[57] CLAIM

The ornamental design for a shipping container, as shown and described.

DESCRIPTION

FIG. 1 is a perspective view of a shipping container showing our new design;

FIG. 2 is a side view thereof;

FIG. 3 is an end view thereof, the opposite view being a mirror image thereof; and,

FIG. 4 is a top plan view thereof, the opposite view being a mirror image thereof.

The broken lines showing a portion of the container are for illustrative purposes only and form no part of the claimed design.
